(57) **CLAIM**

The ornamental design for an egg carrier, as shown and described.

DESCRIPTION

FIG. 1 is a perspective view of an egg carrier of my new design;

FIG. 2 is a top view of the egg carrier of FIG. 1; and

FIG. 3 is a bottom view of the egg carrier of FIG. 1;

FIG. 4 is a front view of the egg carrier of FIG. 1;

FIG. 5 is a back view of the egg carrier of FIG. 1;

FIG. 6 is a right view of the egg carrier of FIG. 1; and,

FIG. 7 is a left view of the egg carrier of FIG. 1.

The broken line portions of the drawings are for illustrative purposes only and form no part of the claimed designs.
